UNITED STATES PATENT OFFICE.

HERBERT O. RUSSELL, OF DETROIT, MICHIGAN, AND CHARLES LEIGH PAULUS, OF DAYTON, OHIO.

OPERATING TRIGGER FOR DOUBLE-GUN MOUNTS.

Application filed April 18, 1922. Serial No. 555,405.

To all whom it may concern:

Be it known that we, HERBERT O. RUSSELL and CHARLES LEIGH PAULUS, citizens of the United States, residing, respectively, at Detroit and Dayton, in the counties of Wayne and Montgomery and States of Michigan and Ohio, have invented certain new and useful Improvements in Operating Triggers for Double-Gun Mounts, of which the following is a specification.

This invention relates to operating triggers for double gun mounts, the object being to produce what may be termed an auxiliary trigger assembly adapted to be used in conjunction with any double gun installation and especially in connection with guns having pistol grips. The auxiliary trigger assembly is adapted to be attached to the trigger guard of one gun and used for controlling the other gun. The improved trigger assembly allows a full hand on the pistol grip, one trigger being operated by the fore finger of the hand and the other by the second finger. The mechanism is particularly adapted for use in connection with the present duplex trigger control for Lewis guns in which the mechanism now used is unguarded and there is therefore a chance for accidental firing.

With the above and other objects in view, the invention consists in the novel construction, combination and arrangement herein described, illustrated and claimed.

In the accompanying drawings:

Figure 1 is a fragmentary side elevation showing the pistol grip of a machine gun and illustrating the auxiliary trigger assembly in its applied relation thereto.

Figure 2 is an elevation of the auxiliary trigger assembly looking from the opposite side.

Figure 3 is an end view of the same.

Referring to the drawings, 1 designates the pistol grip of a machine gun, 2 the trigger of said gun and 3 the trigger guard.

The auxiliary trigger assembly of this invention comprises in the preferred embodiment two oppositely disposed frame pieces or members 4 and 5 to one of which is permanently secured a trigger guard 6. The frame members 4 and 5 are preferably formed so that they may be clamped upon opposite sides of the trigger guard 3 as in-

dicated in Figure 1, said frame pieces being securely held together and in clamping relation to the trigger guard 3 by fasteners 7 which may consist of screws or bolts as may be preferred.

The trigger assembly also comprises a trigger 8 and an operating lever 9. Both members 8 and 9 have a common axis being mounted on a short transverse shaft 10 supported by the frame members 4 and 5. The lever 9 is arranged at one side of the frame of the auxiliary trigger assembly and extends upwardly above the same where it has attached thereto a flexible operating connection 11 such as Bowden wire control which leads therefrom to the other gun (not shown).

In operation the pistol grip 1 is held in the hand with the index finger on the trigger 2 and second finger on the trigger 8. This is a natural position for the hand and allows a pull by a grip of the hand. The trigger assembly is adapted to any double gun installation, and is easily attached to the trigger guard of one gun and connected to the trigger mechanism of the other gun and furthermore the trigger is guarded against accidental firing. The mechanism is particularly adapted for use in connection with the present duplex trigger control for Lewis guns, and eliminates the danger of accidental firing of the guns. The present arrangement requires the use of the last two fingers on the hand. Under such arrangement the gunner is prevented from obtaining a full grip on the gun.

Having thus described my invention, I claim:

An operating trigger for a double gun mount embodying in combination with the trigger guard of one gun, an auxiliary trigger assembly including a frame attached to said trigger guard, a shaft rotatably carried by said frame, a trigger on said shaft, a lever on said shaft extending upwardly above said trigger guard, and an operating connection leading from the upper end of said lever to the control device of another gun.

In testimony whereof we affix our signatures.

HERBERT O. RUSSELL.
CHARLES LEIGH PAULUS.
